UNITED STATES PATENT OFFICE.

SAMUEL W. SAYLOR, OF MEDIAPOLIS, IOWA.

CRUTCH.

1,184,575.

Specification of Letters Patent. Patented May 23, 1916.

Application filed October 9, 1915. Serial No. 54,999.

To all whom it may concern:

Be it known that I, SAMUEL W. SAYLOR, a citizen of the United States, residing at Mediapolis, in the county of Des Moines 5 and State of Iowa, have invented certain new and useful Improvements in Crutches; and I do hereby declare the following to be a full, clear, and exact description of the invention, such as will enable others skilled 10 in the art to which it appertains to make and use the same.

This invention relates to crutches, and the primary object of the invention is to provide a crutch which is foldable, so that the 15 same may be folded into a compact form and placed within a suitcase or like structure when it is desired to carry the crutch from one place to another, without using the same, in which the side or supporting arms 20 of the crutch are constructed of a plurality of pivotally connected sections, the ends of which overlap each other, and to provide sleeves which are slidably mounted upon the supporting arms of the crutch and may be 25 slid over the overlapping end of the pivotally connected section for holding them locked in an extended position, and further to mount enlargements upon the inner surfaces of the sections of the crutch over 30 which the sleeve may be slid when not in use, so as to prevent them from moving longitudinally upon the sections of which the supporting arms of the crutch are formed.

With the foregoing and other objects in 35 view this invention consists in such novel features of construction, combination and arrangement of parts as will be hereinafter more fully described, illustrated in the accompanying drawings and claimed.

40 In describing the invention in detail reference will be had to the accompanying drawings wherein like characters designate like or corresponding parts throughout the several views, and in which:—

45 Figure 1 is a side elevation of the improved crutch showing the same in an extended position. Fig. 2 is an edge view of the crutch, and Fig. 3 is a side elevation of the crutch showing the same in a folded 50 position.

Referring more particularly to the drawing, 1 and 2 designate the supporting arms or legs of the crutch each of which is composed of a plurality of sections 3, 4 and 5. 55 The sections 3, 4 and 5 are constructed of flat metal bars, and the sections 3 and piv-

otally connected to the upper end of the sections 4 by a bolt 6 which extends there-through and through the hand grip 7 of the crutch. The hand grip 7 is constructed 60 in the usual manner, being substantially cylindrical shaped so that a firm grip may be had upon the same during the use of the crutch. The lower ends of the sections 4 are pivotally connected to the upper ends 65 of the sections 5, by a bolt 8. The pivotally connected ends of the sections overlap, so that when they are in an extended position, as shown in Fig. 1 of the drawings, the sleeves 9 and 10 may extend over the upper 70 free ends of the sections 4 and the upper free ends of the sections 5 respectively, for preventing accidental pivotal movement of the sections with respect to each other during the use of the crutch. The sleeves or 75 collars 9 are shaped so that they will fit snugly over the free ends of the sections which project above the pivotal points, and when the crutch is in a folded position, as is shown in Fig. 3 of the drawings, the 80 sleeve rests against or upon pads 11 which are attached to the inner surfaces of the sections 3 and 4. The pads 11 are constructed of any suitable type of material such as leather, rubber or the like which will grip 85 the inner surfaces or bores of the sleeves sufficiently to prevent them from sliding along the sections when the crutch is in a folded position and not in use.

The sections 5 of the crutch arms or sides 90 are bent inwardly toward each other a short distance below the upper ends and are attached to the leg 12 of the crutch. The leg 12 may be constructed of any suitable material and is preferably circular shaped in 95 cross section as is ordinary in forming the lower portions of crutches. Another noiseless, anti-slipping cap 13 is mounted upon the end of the leg or tip 12 of the crutch. The upper end of the section 3 of the crutch 100 legs 1 and 2 are bent outwardly as is shown at 14 and are secured to the under surface of the ends of the arm support 15 of the crutch.

The sections 3, 4 and 5 of the crutch sup- 105 porting legs are straight, so that the lower end of the crutch will be considerably nar- rower than the upper end to which the arm rest 15 is attached, and also so that the point of the pivotal connection between the sec- 110 tions 3 and 4 at which point the hand grip 7 is provided is greater in width than the

upper end of the section of a crutch body forming a crutch of the ordinary shape, so that when the various sections are moved upon their pivotal points for folding the 5 crutch, the section 5 and the tip 12 attached thereto will be positioned intermediate of the sections 4, and the latter sections intermediate of the sections 3, as is clearly shown in Fig. 3 of the drawings.

10. In reducing the invention to practice certain minor features of construction, combination and arrangement of parts may necessitate alteration to which the patentee is entitled provided such alterations are comprehended within the scope of what is claimed.

15. What is claimed is:—

In a crutch structure, crutch legs composed of a plurality of pivotally connected

sections, the ends of said sections extending beyond their pivotal connection, sleeves slidably carried by said sections for extension over said extending ends for holding said sections against accidental pivotal movement with respect to each other, and pads carried by the inner surfaces of certain of said sections and provided for being engaged by said sleeve for preventing accidental slidable movement of said sleeves when said sections are in their folded position.

20. In testimony whereof I affix my signature 25 in presence of two witnesses.

SAMUEL W. SAYLOR.
